Stephen A. Platt, Decatur, Ill., assignor to U. S.
Manufacturing Corporation, Decatur, Ill.

Application June 4, 1935, Serial No. 57,131

Term of patent 14 years

To all whom it may concern:

Be it known that I, Stephen A. Platt, a citizen of the United States and a resident of Decatur, in the county of Macon and State of Illinois, have invented a new, original, and ornamental Design for an Electric Corn Popper, of which the following is a specification, reference being had to the accompanying drawing, forming part thereof.

In the drawing:—

Figure 1 is a top plan view, and

Figure 2 is a perspective view of the electric corn popper, showing my new design.

I claim:

The ornamental design for an electric corn popper as shown.

STEPHEN A. PLATT.
